UNITED STATES PATENT OFFICE

LARRY VENDITTI, OF PHILADELPHIA, PENNSYLVANIA

DESIGN FOR AN AQUARIUM

Application filed October 17, 1930. Serial No. 37,284. Term of patent 14 years.

To all whom it may concern:

Be it known that I, LARRY VENDITTI, a citizen of the United States, residing at Philadelphia, in the county of Philadelphia and Commonwealth of Pennsylvania, have invented a new, original, and ornamental Design for Aquarium, of which the following is a specification, reference being had to the accompanying drawing, forming a part thereof.

Figure 1 is a top plan view of the new aquarium,

Figure 2 is a view in front elevation, as indicated by arrow 2, at Figure 1, and

Figure 3 is a view in side elevation, as indicated by arrow 3, at Figure 1.

I claim:

The ornamental design for an aquarium, as shown.

LARRY VENDITTI.
